CLAIM

The ornamental design of a mounting frame, substantially as shown and described.

DESCRIPTION

FIG. 1 is a perspective view of a mounting frame according to our design;

FIG. 2 is a perspective view thereof shown with environmental subject matter;

FIG. 3 is a top view thereof, the bottom view being a mirror image;

FIG. 4 is a top view thereof shown with the panel doors open, the bottom view being a mirror image; and,

FIG. 5 is a front view thereof, the right, rear, and left sides being a mirror image.

The broken lines shown in the drawings are included for the purpose of illustrating environmental structure and form no part of the claimed design.
